(57) **CLAIM**

The ornamental design for a shoe storage cabinet, as shown and described.

DESCRIPTION

FIG. 1 is a front elevational view of a shoe storage cabinet showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof;

FIG. 8 is another perspective view thereof;

FIG. 9 is a perspective view of the shoe storage cabinet where the shoe storage cabinet is in an open state; and,

FIG. 10 is another perspective view thereof.

The broken lines in the drawings depict portions of the shoe storage cabinet that form no part of the claimed design.
